(57) **CLAIM**

The ornamental design for a scooter kickstand, as shown and described.

DESCRIPTION

FIG. 1 is a top, rear, left-side perspective view showing a scooter kickstand of my design;

FIG. 2 is an enlarged partial view thereof, taken from FIG. 1;

FIG. 3 is a bottom, front, left-side view thereof;

FIG. 4 is a left-side view thereof;

FIG. 5 is a right-side view thereof;

FIG. 6 is a front view thereof;

FIG. 7 is a rear view thereof;

FIG. 8 is a top view thereof; and,

FIG. 9 is a bottom view thereof.

The dot-dash line in FIG. 2 represents the boundary of the enlarged partial view. All other broken lines are for the purpose of illustrating the environment in which the article resides. None of the broken lines form a part of the claimed design.
